UNITED STATES PATENT OFFICE.

FRIEDRICH SOCHOR, OF VIENNA, AUSTRIA-HUNGARY.

GRAB FOR TRANSPORTERS, EXCAVATORS, AND THE LIKE.

1,142,637.

Specification of Letters Patent.

Patented June 8, 1915.

Application filed July 22, 1911. Serial No. 639,913.

To all whom it may concern:

Be it known that I, FRIEDRICH SOCHOR, a subject of the Emperor of Austria-Hungary, residing at Vienna, Empire of Austria-Hungary, have invented certain new and useful Improvements in Grabs for Transporters, Excavators, and the like; and I do hereby declare the following to be a full, clear, and exact description of the invention, such as will enable others skilled in the art to which it appertains to make and use the same.

This invention relates to grabs with variable gearing specially suitable for the handling of material in large pieces. The drawbacks of such grabs as previously constructed reside in their great height necessary to obtain a sufficiently large opening, great weight owing to the considerable power required to close the jaws of the grab, and the consequence is that the crane is compelled to transport a considerable total weight.

The object of the present invention is to overcome the above drawbacks and to devise a construction of grabs of small height, of reliable and very wide opening, and large and variable gearing for the closing of the jaws.

The invention consists in an improved grab of the above type in which the bucket halves are mounted on arms pivoted near the ends of a long upper horizontal supporting bar, and cranks are mounted on the supporting bar which cranks are connected through connecting rods with the arms while ropes pass over guide drums mounted at the ends of the supporting bar to attachment points on the arms, for the purpose of effecting a large opening of the bucket halves which latter separate owing to their own weight, their additional opening being effected only to a small extent by the pull of the said ropes.

The invention is illustrated by way of example in the accompanying drawings, in which:—

Figure 1 is an elevation, Fig. 2 a plan, Fig. 3 an end elevation, and Fig. 4 a side elevation of the grab in opened position, Fig. 5 is a side elevation, Fig. 6 a plan of a modification.

In the drawings *a* denotes a long horizontal supporting bar at the ends of which are pivoted arms *b* *b* and *b*¹ *b*¹ for the two bucket halves *c* and *c*¹, rigidly attached to the said arms. The arms are pivoted to the bar *a* on pins *d* *d* and *d*¹ *d*¹. The devices for

the closing and opening of the bucket halves are separate.

The opening device comprises cranks *h* *h* and connecting rods *f* *f* and *f*¹ *f*¹ arranged with a view to the rigid coöperation of the bucket halves, and driving ropes *k* *k* attached outside to the arms or to the cranks *h* *h*. The operation of the mechanism is the same whether the opening ropes *k* are attached to the cranks *h* as shown in dotted lines in Fig. 1 or whether they are directly attached to the arms *b* *b*, *b*¹ *b*¹. In the former case by pulling the opening ropes *k* the cranks *h* *h* are so turned around their axis *l* that the pins *g* are moved to the left and the pins *g*¹ to the right along substantially horizontal lines whereby the pins *e* *e*' are caused to move to the left and right respectively so that the bucket halves are opened. In the latter case, that is to say, when the opening ropes are attached to the arms *b* *b*, *b*¹ *b*¹, say to the pins or bolts *e* *e*', then on pulling the opening ropes these pins or bolts *e* *e*' move in the same direction as in the former case, whereby the bucket halves are opened and through the medium of the connecting rods *f* and *f*¹ the cranks are turned around the axis *l* in the same direction as in the former case. Consequently it makes no difference at all whether the opening ropes *k* are attached to the cranks or directly to the arms *b* *b*, *b*¹ *b*¹. These cranks may be as in the present case loosely mounted on a shaft *l* journaled in the supporting bar *a*. When the ropes *k* *k* are attached to the cranks, these are formed as shown in dotted lines in Fig. 1 and the ropes are attached to pins *i* *i* while the connecting rods *f* *f* and *f*¹ *f*¹ are jointed at one end to pins *g* *g* and *g*¹ *g*¹ on the cranks and at the other end to pins *e* *e* and *e*¹ *e*¹ on the bucket arms. In the other case however, the pins *i* *i* are omitted and the ropes are attached to any suitable point on the arms *b* *b* and *b*¹ *b*¹, such as to bolts *e* and *e*¹ whence they pass over rollers *w* *w* journaled in the end of the supporting bar *a*. By means of the connecting rods which are positively connected to the cranks mounted on the supporting bar *a* the position of the two bucket arms with respect to the bar *a* and to each other is exactly and positively determined so that a tilting or displacement of the supporting bar *a* owing to the resistance encountered by the edges *v* and *v*¹ in the material to be transported, is impossible and any position

other than the symmetrical position of the bucket halves with respect to the center line cannot occur.

The closing mechanism consists of pulleys 5 s s^1 and t t^1 mounted in brackets u u attached to the arms b b and b^1 b^1 , from which pulleys ropes r r pass over two drums o o . These latter and the two closing drums n n are mounted on a shaft m also journaled in 10 the supporting bar a . To protect the ropes r r from becoming worn through contact with the material, a shield y is provided which also acts to prevent the grab from sinking too deeply in the material. The 15 grab is thus protected from excessive overloading and the shield distributes the material picked up by pushing against the outer ends of the bucket halves.

The supporting bar a is made so long that 20 when the grab is closed the pivots d and d^1 lie nearly above the outer ends of the bucket halves so that the whole width is utilized and, moreover, owing to the position of the bucket halves on the arms to which they are 25 rigidly connected and the suspension of the latter at the ends of the long support a , the surfaces of the bucket halves even when the grab is widest open are not directed vertically against the material but assume a 30 favorable position for shoveling up the material. With the improved construction the result is that the opening takes place at first owing to the weight of the bucket halves since they when the closing ropes are slack 35 swing by themselves about the pivots d and d^1 into the position of equilibrium. In the second place the opening of the bucket halves is very large with even a small angle 40 of rotation as in consequence of the far-out position of the pivots d and d^1 the arms b and b^1 are very long so that the edges v and v^1 of the grab describe a long arc with even 45 a small angle of rotation. By simultaneously pulling the opening ropes k k , the toggle lever effect of the crank h h and the connecting rods f f and f' f' or the direct pull of the opening ropes k k on the arms b b and b' b' , is exerted to the greatest extent, exactly at the last instant when the 50 bucket halves have swung past the position of equilibrium and their weight again opposes their opening. When the grab is to be closed the opening ropes k k are released and the closing ropes p p pulled.

55 In the modification shown in Figs. 5 and 6, two cranks are used which are compelled to turn simultaneously through the same angle in opposite directions by toothed seg-

ments h and h' fast on the shafts l m of the said cranks and gearing into each other. 60 The connecting rods f f' connect the crank pins g and g' to the arms b b' of the bucket halves c c' at e e' and rods i i' pivotally connect the crank pins g g' to the opening ropes k k . For opening the grab the rope p 65 is slackened, the grab opens by gravity owing to the fact that its rods are pivoted to the outer ends of the long horizontal supporting bar until the pins g , g' have passed beyond their lowermost or dead center position, whereupon by pulling the opening ropes k k further movement of the cranks and connecting rods f f' is caused. 70

In all of the cases above described the 75 crank pins g g' move relatively to the supporting bar a and in a direction substantially parallel to the longitudinal axis of such bar.

The technical advantages of the hereinbefore described improved grab may be briefly 80 summarized as follows: (a) Small overall height owing to the attachment of all the members to an upper horizontal support. (b) Exceptionally easy and reliable opening 85 owing to the location far out of the pivoting points of the bucket halves and the powerful pull or toggle lever effect at the end of the opening motion. (c) Unusually wide opening due to the long bucket arms permitted by position of the pivoting points. 90 (d) Favorable operation of the closing forces by utilizing the changing height of the pulleys during the closing motion and the thereby obtained variable velocity ratio. 95

Claim:

In a grab, the combination of a horizontal supporting bar having pulleys at its outer ends, arms pivoted at their inner ends near the said outer ends of such bar and having rigidly secured to their outer ends bucket 100 halves, cranks, revolubly mounted on the said bar adjacent its center, connecting rods, connecting such cranks with the said arms and engaging the latter intermediate the ends thereof, and means for separating the 105 bucket halves including ropes connected to said cranks and other ropes extending downwardly around the said bar pulleys and connected to the arms intermediate the ends of the latter.

In testimony whereof, I affix my signature, in presence of two witnesses.

FRIEDRICH SOCHOR.
